UNITED STATES PATENT OFFICE.

ADRIAN C. SCHARFF, OF ORANGE, CONNECTICUT.

DESIGN FOR A SMOKER'S STAND.

Application filed November 20, 1925. Serial No. 15,480. Term of patent 7 years.

To all whom it may concern:

Be it known that I, ADRIAN C. SCHARFF, a citizen of the United States, residing at Orange, in the county of New Haven and State of Connecticut, have invented a new, original, and ornamental Design for Smokers' Stands, of which the following is a specification, reference being had to the accompanying drawing, forming part thereof.

Fig. 1 is a side elevational view of a smoker's stand, showing my new design;

Fig. 2 is a plan view thereof;

Fig. 3 is a fragmentary front elevational view; and

Fig. 4 is a fragmentary rear elevational view.

I claim:

The ornamental design for a smoker's stand, as shown.

ADRIAN C. SCHARFF.
